FRONT FEED DEVICE FOR BUSINESS OFFICE MACHINES

Andreas Salzberger, Frankfurt am Main, Germany, assignor to Torpedo-Werke Aktiengesellschaft Fahrrader und Schreibmaschinen, Frankfurt am Main Rödelheim, Germany, a German company

Application August 17, 1953, Serial No. 374,741

Claims priority, application Germany August 16, 1952

8 Claims. (Cl. 197—127)

The invention relates to front feed devices for business writing machines, for introducing one or more cards or the like from the front in front of a basic sheet situated in the machine. These front feed devices are provided with separate draw-in rollers for each feed chute for drawing in the cards, the cards being drawn in by the drive of said rollers and a spring motor being wound up at the same time which, after release, returns the draw-in rollers to the basic position and hence ejects the drawn-in card after lettering. These front feed devices are furthermore provided with punching devices, which after each lettering of a card, punch in the latter a notch, hole or slot. Associated with the feed chutes is a feeler lever which, on the drawing-in of a card, slides over the latter and then drops into the slot punched out in the preceding operation, is carried along by the card and locks the drive of the draw-in rollers, the arrangement of the parts being such that the locking of the draw-in rollers occurs precisely when the next writing line of the card is at the level of the writing line of the machine. In the known devices of this kind, the feeler finger is carried along by the card merely by its engagement in the hole of the latter, or is controlled by the draw-in rollers by means of a wiping spring for moving along with the card. In both constructions, the feeler finger whilst being moved along by the card, bears against the upper edge of the hole, the outward pivotal movement of the feeler finger being initiated substantially by the card, even in the case of the use of a friction spring. Since the feeler finger has to overcome a certain resistance, tearing of the control holes of the card readily occurs, which results in inaccurate positioning of the card.

The invention concerns a new construction of such a front feed device with feeler finger control of the drive of the draw-in rollers, in which the movement of the feeler finger is independent of both the draw-in movement of the card and the rotation of the rollers drawing in said card, so that the feeler finger by its own movement in the control hole of the card moves along with the latter and in an end position, locks the drive of the draw-in rollers. Any tearing of the card perforations by the feeler finger is thereby prevented, so that front feed sheets of thin paper can be drawn in reliably as far as the line to be lettered in each case.

According to the invention, in front feed devices of the type specified, the feeler finger is adapted to be loaded by a spring in the draw-in direction, which with the drive of the draw-in rollers is released for the duration of the drive by a member controlled by the latter for action on the feeler finger. On release, the loading spring brings the feeler finger to bear on the card, so that on moving past the hole in the card, it is pushed into the latter, and with the further movement of the hole, is swung out by the spring so that, under the influence of the spring, it operates the locking device for the draw-in rollers. With the stopping of the drive which

2

thereby follows, the member influenced by the latter returns to the basic position, whereby the loading spring is removed from the feeler finger so that, with the ejection of the card, said feeler finger returns to the basic position under the effect of a return spring acting on it.

The new construction will be explained more fully with further features, with reference to the accompanying drawings, in which.

Fig. 1 shows the basic position of the front feed device,

10 and

Fig. 2 shows the working end position in cross-section through a front feed device.

The constructional example concerns a double front feed device with two card chutes 1, 2, bounded by the 15 central partition 3 and the two guide plates 4 and 5. On its lower side, the partition 3 carries the two punching plates 6, 7 for the perforating device not shown, below which is provided a collecting box 8 for the punched out pieces.

20 The two guide plates 4, 5 are provided with openings 9, 10 for the passage of the perforating punches, not shown, and above said openings the guide plates have slots 11, 12 for the passage of feeler fingers 13, for which recesses 14, 15 are provided in the partition 3. 25 The construction of the parts so far described is known per se.

Following the outlet end of each chute 1, 2 is a feed roller 16, 17, each of which co-operates with a press-on roller 18, 19. Each feed roller 16, 17 is adapted to be driven by a hand lever through a transmission and is coupled to a spring motor which, on the rollers being driven, is wound up in the draw-in direction, and can be released by a release key after the lettering of the cards for the ejection of the latter.

30 On the spindle of each feed or draw-in roller 16, 17 is a ratchet wheel 20, 21. By engagement of pawls 22 and 23, respectively, in the ratchet wheels 20, 21, the draw-in movement of the feed rollers 16, 17 is stopped, and hence the draw-in distance of the front feed sheets fed by them is determined.

35 To ensure the application of the front feed sheets drawn into the machine against the platen of the machine, there is provided a bar 24, which extends over the entire front feed device and is swung out of the position shown in Fig. 1 into the position shown in Fig. 2 by a control cam of the drive for the rollers 16, 17 at the commencement of the draw-in movement. The pawls 22, 23 are controlled by the feeler fingers 13.

40 These draw-in devices are also known fundamentally.

45 The two feeler fingers 13 are pivotally mounted by means of eyes 25 on supporting spindles 26, which are received by covers, not shown, secured to the guide plates 4, 5. The feeler fingers 13 are under the action of return springs 27 which tend to hold the fingers 13 in the basic position as shown in Fig. 1, in which position the fingers are situated outside the feed chutes 1, 2.

50 The pawls 22, 23 are pivoted on supporting spindles 28 and are under the action of springs 29, tending to hold them out of engagement with the ratchet wheels 20, 21. The pawls 22, 23 are controlled by noses 30 of the eyes 55 25 of the feeler fingers 13 engaging below projections 31 of the pawls.

55 Accommodated in the casing receiving the feeler finger 13 and the pawl 22 for the front chute 1 is also a third spindle 32, on which a control member 33 is guided by means of a slot 34 for sliding and outward-swinging. The control member 33 has two adjacent recesses 35, 36, co-operating with the supporting spindle 28, and is influenced by a spring 37 in the direction of the spindle 28, so that it is held with the inner recess 35 on the spindle 28 (Fig. 1). Furthermore, the control member 33 has a 60 downwardly extending finger 38 with a recess 39 which,

in the basic position (Fig. 1) lies in the path of the bar 24. The control member is thus lifted by means of the bar 24 as it swings from the position shown in Fig. 1 into the position shown in Fig. 2 with the drive of the feed rollers 16, 17 (Fig. 2).

The finger 38 of the control member 33 projects beyond the casing housing the device. The control member 33 can thus be swung by hand by means of the finger 38 from the position shown in Fig. 1 to the right, so that the recess 36 is supported on the spindle 28. In this position of the control member 33, the recess 39 lies outside the path of swing of the bar 34 and is thus not affected by the latter on the actuation of the draw-in rollers 16, 17 in the feed direction. By this change-over of the control member 33, therefore, the feeler device can be put out of action.

The supporting spindle 32 for the control member 33 also carries a tension spring 40, one arm 41 of which bears against the spindle 28, whilst the other arm 42 co-operates with a bent-over portion 43 of the eye 25 of the feeler finger 13. The spindle 26 carrying the eye 25 of the feeler finger 13 carries pivotally an intermediate lever 44, which is guided by means of a pin 45 in a slot 46 of the control member 33, and has a nose 47 engaging over the arm 42 of the tension spring 40. Furthermore, the intermediate lever 44 is so formed that, in the basic position (Fig. 1) it holds the arm 42 of the tension spring 40 free from the bent-over portion 43 of the eye 25 of the feeler finger 13. The feeler finger 13 is thus only under the influence of the return spring 27 and is held by the latter outside the chute 1 (Fig. 1).

With the commencement of the draw-in movement of the feed roller 16, the control member 33 is lifted by the outwardly swinging bar 24 from the position shown in Fig. 1 to the position shown in Fig. 2. At the same time, the intermediate lever 44 is pivoted in the anti-clockwise direction and thus releases the tension spring 40 for action on the feeler finger 13. The latter is swung by the spring 40 towards the feed chute 1 and pressed against the card drawn in the latter. The feeler finger 13 is thus inserted by the tension spring 40 into the oncoming hole of the front feed card and is forced by the spring 40 to make a following movement with the hole. With this pivotal movement of the feeler finger, which is independent of the draw-in rotation of the feed roller 16, the pawl 22 is brought by the nose 30 into engagement with the ratchet wheel 20, and hence the draw-in movement of the feed rollers is stopped.

With the release of the lever releasing this draw-in movement, the bar 24 also returns to the basic position. The control member 33 thus also returns to the basic position shown in Fig. 1, in which the feeler finger 13 is loaded only by the return spring 27. As soon as the front feed card after lettering is released for ejection, the return spring 27 also brings the feeler finger 13 to the starting position.

For controlling the tension spring 40a for actuating the feeler finger 13 of the rear feed chute 2, there is provided an intermediate lever 49, which is pivoted on a shaft 48 and which controls the tension spring 40a and is coupled to the intermediate lever 44 by a rod 50.

I claim:

1. A front feed device for business office machines comprising draw-in rollers for feeding a front feed sheet having at least one perforation therein, a feeler finger movable between an inoperative position remote from the feeding path of the front feed sheet and an operative position projecting across said path for engaging in a perforation of the front feed sheet to move with the latter during the feeding of the sheet, locking means effective to limit the rotation of said draw-in rollers in response to movement of said finger with the front feed sheet in the direction of feeding of the latter, spring means operative to urge said finger to said operative position thereof and in the direction of feeding of the front feed sheet, and control means normally rendering said spring means in-

operative and effective, during the operation of said draw-in rollers, to release said spring means for urging said finger in the direction of feed of the sheet so that the tendency of the finger engaged in a perforation of the sheet to tear the sheet is thereby avoided.

5 2. A front feed device according to claim 1; further comprising return spring means yieldably urging said feeler finger to said inoperative position of the latter, said return spring means being weaker than the first mentioned spring means so that, when the latter is released by said control means during the operation of the draw-in rollers, said first spring means overcomes the effect of said return spring means on said feeler finger.

3. A front feed device according to claim 2; wherein 15 said first spring means includes a torsion spring member having two arms which tend to move angularly apart, one of said arms being anchored and the other of said arms being engageable with said feeler finger to urge the latter in the feeding direction of the front feed sheet; and 20 wherein said control means includes a movable control member normally bearing against said other arm of the torsion spring member to hold the latter out of engagement with said feeler finger, and means displacing said control member away from said other arm of the torsion spring member in response to operation of said draw-in rollers.

4. A front feed device according to claim 3; wherein 25 said means displacing the control member includes a control slide, a press-on bar swinging away from the feeding path of the front feed sheet during the operation of said draw-in rollers, said control slide having a portion thereof normally extending into the swinging paths of said press-on bar to be engaged by the latter so that the control slide is lifted by swinging of said bar away from the feeding 30 path, and coupling means between said control member and control slide arranged so that lifting of the latter causes displacement of said control member away from said other arm of the torsion spring member.

5. A front feed device according to claim 4; further 40 comprising a supporting spindle, said control slide having a first recess opening downwardly and adapted to receive said supporting spindle, and resilient means connected to said control slide and yieldably resisting the lifting of the latter so that said control slide is normally supported on 45 said spindle in said first recess during the periods when said draw-in rollers are inoperative and said press-on bar is disposed adjacent the feeding path.

6. A front feed device according to claim 5; wherein 50 said control slide has a slot therein, and further comprising a guide spindle engaged in said slot to guide the lifting movement of said control slide, said control slide being rockable about said guide spindle in said slot to dispose said portion of the control slide out of the swinging path of said press-on bar so that said control member 55 will then continue to bear against said other arm of the torsion spring member to hold the latter out of engagement with the feeler finger even during the operation of said draw-in rollers.

7. A front feed device according to claim 6; wherein 60 said control slide has a second downwardly opening recess spaced laterally from said first recess and adapted to receive said supporting spindle for maintaining said control slide in an inoperative rocked position in which said portion of the control slide is disposed out of the 65 swinging path of said press-on bar.

8. A front feed device according to claim 7; further 70 comprising draw-in rollers for feeding a rear feed sheet having at least one perforation therein, a rear feeler finger movable between an inoperative position remote from the feeding path of the rear feed sheet and an operative position projecting across said path of the rear feed sheet for engaging in a perforation of the rear feed sheet to move with the latter during the feeding of the rear feed sheet, locking means effective to limit the rotation of said 75 draw-in rollers for the rear feed sheet in response to

movement of said rear finger with the rear feed sheet in the direction of feeding of the latter, spring means operative to urge said rear finger to said operative position thereof and in the direction of feeding of the rear feed sheet, return spring means for urging said rear finger to its inoperative position when the first mentioned spring means associated with said rear finger is inoperative, a movable control member engageable with said first spring means associated with the rear finger, and a connecting link between the first mentioned control member and the last mentioned control member so that the latter is actuated by said first control member and renders inopera-

tive, and releases, said first spring means associated with said rear finger in response to the movement of said first control member against and out of engagement with, respectively, said other arm of the torsion spring member associated with the feeler finger for the front feed sheet.
